(57) **CLAIM**

The ornamental design for a jump ring, as shown and described.

DESCRIPTION

FIG. 1 is a front view of a jump ring;

FIG. 2 is a back view thereof;

FIG. 3 is a top view thereof;

FIG. 4 is a bottom view thereof;

FIG. 5 is a right view thereof;

FIG. 6 is a left view thereof; and,

FIG. 7 is a front perspective view thereof.

Broken lines shown in drawings illustrate portions of the jump ring that form no part of claimed design.
